ELECTRON TUBE AND FILAMENTARY CATHODE

Merrald B. Shrader, Mount Joy, Pa., assignor to Radio Corporation of America, a corporation of Delaware

Application June 5, 1953, Serial No. 359,770

13 Claims. (Cl. 313—273)

This invention relates to electron tubes and more particularly to such tubes having a filamentary type cathode.

Filamentary cathodes are characterized by dependable electron emission over an exceedingly long useful life. Furthermore, such filaments have successfully been utilized in tubes having a wide range of power output capabilities even though relatively complex arrangements are required. While filamentary cathodes have come to be more widely used in power tubes than indirectly heated or unipotential cathodes, this is not the case with respect to high frequency tubes. The filamentary cathode structures heretofore utilized, in addition to having certain mechanical disadvantages, have also been unsuitable for use at the higher frequencies.

One of the disadvantages of the structures heretofore utilized may be best pointed out in connection with the so-called self-supporting filamentary structure. In such a structure filamentary strands are usually arranged around a circle with adjacent strands extending parallel to one another. The adjacent strands are connected at one end to different heating current lead-ins while at their opposite ends the strands are bound together to form the self-supporting structure. The heating current which heats the filament strands to electron emission temperature travels up alternate strands to the bound ends and then down the remaining strands. One of the filament heater lead-ins serves also as the radio frequency current lead-in thereby resulting in the radio frequency current traveling up alternate strands and then down the remaining strands. Obviously such an arrangement is limited to relatively low frequencies since otherwise the electrical phase difference between adjacent strands would be found objectionable. Furthermore, the low frequency heating current e. g., 60 cycles, usually utilized adversely affects the operation of such tubes and its harmful effects must be overcome. Often this is extremely difficult and costly to carry out.

Some of the foregoing short comings are ameliorated by utilizing a central support connected to the bound ends or electrical center of the filamentary strands. The center tap thus provided may be utilized as the radio frequency lead-in or connection to the filament structure. However, such a structure also is limited to relatively low frequency. As is well known, with increasing frequency the elements of a tube become more and more a significant part of the high frequency circuit. The inductance of leads and filament strands becomes a major portion of the circuit and effectively limits the upper frequency of operation.

While the filamentary type of cathode structure is widely used, the structures utilized have often proven to be fragile and subject to deformations which have limited their usefulness.

It is therefore a principal object of my invention to provide an improved electron tube having a substantially unipotential filamentary cathode.

Another important object is to provide an electron

2

tube having a substantially unipotential filamentary cathode and capable of operation at high frequencies.

Still another object is to provide an electron tube having a substantially unipotential filamentary cathode capable of operation at high frequencies and high power.

Another object is the provision of an electron tube in which the filament heating current leads are completely shielded from the radio frequency current leads and do not themselves carry any radio frequency current.

Yet another object is the provision of an electron tube having a substantially unipotential filamentary cathode and having reduced overall dimensions.

Stated generally, I provide a pair of filament heating current lead-ins which extend into the electron tube envelope and to each of which are connected filament support rods. Alternate support rods are connected to one lead-in while the remaining support rods are connected to the other lead-in. I utilize filament strands which are doubled over or joined together at one end so as to form interconnected pairs. The free ends of the doubled over or paired filament strands are each connected to adjacent support rods while the strands themselves extend back along the support rods. A tubular radio frequency lead-in is sealed through the envelope so as to completely shield the heating current lead-ins from the remaining lead-ins and elements of the tube which may include control electrode, screen electrode, and anode lead-ins and electrodes. The filamentary cathode radio frequency lead-in extends into the envelope and is conductively connected to each of the filament strands at their electrical center. In such an arrangement the radio frequency currents travel up all of the filamentary strands in phase and do not travel along the filament support rods at all. Thus the electrical length of the cathode structure with respect to radio frequency is that of the radio frequency lead-in and the filament strands themselves. The electrical length of the support rods is not included at all.

My invention as well as further objects and advantages thereof will be most clearly understood from the following description thereof and the accompanying drawings in which:

Figure 1 is a sectional view of an electron tube constructed in accordance with my invention;

Figure 2 is a fragmentary sectional view through the line 2—2 of Figure 1;

Figure 3 is a fragmentary perspective view of a portion of the filament structure;

Figure 4 is a sectional view of yet another filament and filament support structure constructed in accordance with my invention; and

Figure 5 is a fragmentary perspective view of a filament structure similar to that shown in Figure 4.

Referring now to the drawings in detail and to Figures 1, 2 and 3 in particular, electron tube 10 comprises a filamentary cathode 11, anode 12, and may also include control electrode 13 and screen electrode 14. The control and screen electrodes 13, 14 themselves may be of any suitable form as is well known in the art and need not be described in detail here. Anode 12 in the present instance forms part of the envelope of tube 10 and may be provided with an array of cooling fins 15, as shown, to form a radiator through which a coolant such as air may be forced under pressure.

Extending into the recess formed by anode 12 are a plurality of filament support rods 16, and 16a which may be molybdenum and are arranged alternately in an annular array in the present instance. All of the support rods 16 are joined at one end as by welding to a support ring 17 which may be of molybdenum or tungsten or the like. Support rods 16a extend through holes or recesses in support ring 17 and are joined to a similar

support ring 18. A pair of nested coaxial tubular lead-ins and supports which may be copper are sealed through the envelope of tube 10. Lead-in and support 19 is joined at its inner end to support ring 17 while lead-in and support 20 is joined to support ring 18. Insulating support means may be provided between the supports 19, 20. For example, an insulating bushing 21 which may be of ceramic or other suitable material may be utilized as a spacer between the inner ends of supports 19 and 20. Bushing or spacer 21 may be shouldered as shown so as to provide additional support for support ring 17. An annular metallic member 22 which may be readily sealed to glass is joined as by brazing or the like to support member 20 adjacent the outer end thereof. Member 22 is sealed as by means of glass bushing 23 to another annular metallic member 24 which also may be readily sealed to glass and which is in turn sealed to support member 19 adjacent the outer end thereof. The specific composition of members 22 and 24 does not form a part of my present invention. These as well as other metallic members to be described which are sealed to insulating members to form part of the tube envelope may be of any suitable metal or alloy, as for example any of the well known alloys of cobalt, nickel and iron.

Support member 19 extends outwardly beyond member 20 and its outwardly extending portion or, as shown, a terminal cap 25 serves as a contact or terminal for one of the filament heater connections. As shown, the terminal member or cap 25 may have an outer diameter which is substantially equal to that of the outwardly extending portion of support 20 which serves as the terminal member for the other side of the heating current circuit. Intermediate the ends of support 20 and inwardly of the portion thereof which serves as a terminal, an annular member 26 is sealed thereto and serves to support an annular terminal member 27 which is somewhat U shaped in cross section. Members 26 and 27 form part of the envelope of tube 10 and are insulatingly joined together as shown at 28 by glass or other suitable material. It should be noted that terminal member 27 forms the innermost portion of a re-entrant part of the envelope of tube 10 as shown.

A tubular or cylindrical conductive member 29 is joined to and supported on terminal member 27 and extends inwardly and engirdles the end portions of support members 19 and 20 as well as support rings 17 and 18 which extend inwardly of terminal member 27. A plurality of filaments 30, one of which is most clearly shown in Figure 3, are provided. Each filament 30 has a pair of parallel portions or strands 31 and 32. The free end of each of the strands 31 is connected to the end portion of one of the support rods 16 as by means of molybdenum clips 33 which are welded thereto. The free end of each of the strands 32 is similarly connected to one of the support rods 16a. In the present instance filaments 30 are each unitary and are doubled back somewhat in the form of a hairpin to form the parallel extending portions 31, 32. Each of the filaments 30 is connected at its midpoint to conductive member 29 by means of thin, flexible radio frequency connectors or straps 34 which may be tantalum or other suitable refractory or high melting point metal. The flexible straps or connectors while serving to rigidify and strengthen the filament structure also permit elongation and contraction of the filaments without causing deformation. As clearly shown portions 31 and 32 of each of the filaments 30 extend back along support rods 16, 16a. The array formed by the support rods and the array formed by the filament strands are thus arranged in side-by-side spaced relation. As will be more fully pointed out, such a filament structure may be made so as to

have such an extremely short electrical length as is desirable and necessary at the higher frequencies.

An annular terminal member 35 has one peripheral portion insulatingly sealed to a peripheral portion of terminal member 27. Terminal member 35 may serve as part of the electrical lead-in and support for control electrode 13 which may be supported therefrom as shown by conductive tubular member 36. The other peripheral portion of terminal member 35 is insulatingly sealed to terminal member 37 which is also annular and serves to similarly support screen electrode 14 by means of conductive tubular member 38.

While the radiator formed by fins 15 may serve as the anode terminal, in the present instance terminal member 39 is preferably provided. Terminal member 39 has one end portion thereof sealed to anode 12 while the other end thereof is sealed to one end of tubular insulator 40 which may be glass. The other end of tubular insulator 40 is sealed to an end portion of terminal member 37.

The envelope and terminal structure of tube 10 embodies several important advantages. Terminals 27, 37 and 39 are all interposed in the envelope wall and are preferably of highly conductive material or plated with silver or other suitable highly conductive material. Such terminals provide low impedance paths and particularly provide low impedance paths to high frequency currents. All of the terminals including also the filament heater terminals 20 and 25 are arranged to facilitate the axial mounting and dismounting of the tube in its circuit.

Another important advantage of such a tube structure resides in the relatively short overall axial length which is made possible by the re-entrant arrangement shown. More particularly the re-entrant structure is provided by the fact that all of the filament terminals including the high frequency terminal 27, are nested within other parts of the envelope structure. Tubular insulator 40 which necessarily must be relatively long to afford proper insulation between terminals 39 and 37 does not add to the overall axial length of tube 10. This is made possible because of the arrangement of terminal 35 as well as most of the filament support structure within tubular insulator 40. As shown terminal 35 is of substantially smaller diameter than the diameter of insulator 40 and is nested within insulator 40 and adjacent the portion thereof connected to terminal 39. The radio frequency filament terminal 27 is seen to be also nested within insulator 40 and is substantially in alignment with anode terminal 39. Filament heater terminal 20 is seen to be located entirely within insulator 40 while the other heater terminal 25 is substantially aligned with terminal 37. Thus, it is apparent that the structure combines the advantage of long glass or leakage paths with short overall tube or lead length.

A further advantage accrues from the construction of radio frequency terminal 27. Because of the well known skin effect at the high frequencies, losses which occur along a conductor increase not only with power but also with frequency. In the case of radio frequency conductors which are sealed through insulators it is necessary to avoid excessive power loss. Such power loss is manifested by the generation of heat in the conductor, which, if excessive, results in damage to or destruction of the seal. In the present instance the radio frequency terminals or leads which are sealed through or form part of the envelope wall of tube 10 are readily provided with sufficient surface area to avoid excessive losses. In particular, the filament radio frequency terminal 27 and the seals associated therewith may be made large enough in diameter in accordance with the present invention so as to prevent excessive seal heating and circuit losses.

Another important advantage accrues from the fact that such a tube may be mounted in its circuit with con-

nections to the filament being made by a low impedance uniform coaxial transmission line. The conductor making contact with terminal 27 may be a tubular member which surrounds the heater current conductors which make contact with heater terminals 20 and 25. Thus the radio frequency input conductor and terminal 27 encloses the heater circuit members and together with conductive member 29 effectively shields the radio frequency circuit and tube elements from the filament heating circuit.

Terminal member 27 and conductive member 29 provide the radio frequency connection to each of the filaments 30. Thus, the radio frequency current travels up the parallel strands or portions 31, 32 of each of the filaments 30 in the same direction. Such currents do not flow at all along support rods 16, 16a or any of the appurtenances of the filament heater circuit which include also support rings 17, 18 and supporting conductor 19, 20. The filament heating current flows along terminal 25, support 19, support ring 17 to each of the filament support rods 16. From support rods 16 the heating current flows to each of the strands or portions 31 then back along portions 32 to support rods 16a. The filament heating current path within the tube is completed from support rod 16a to support ring 18 and conductive support 20. It is obvious then, that the cathode portion of the radio frequency circuit within tube 10 includes only terminal 27, conductive member 29, connectors 34, and strands 31, 32, while electrical length of the filament support structure is excluded and does not add to the electrical length thereof. Therefore, the filament support structure may be modified as by lengthening the same without adversely affecting the radio frequency characteristics of the device. The importance of this will be more readily appreciated when it is understood that the length of the support structure is often dictated by other factors, such as for example proper thermal isolation of various seals, as well as the desired frequency of operation.

In Figures 4 and 5 there is shown another filament and filament support structure together with its leads and terminal members which embodies some of the advantages and features described hereinabove. A plurality of filament strands 50 are arranged in an annular array. Strands 50 are connected in pairs around the array adjacent the lower ends thereof as shown. The free ends of alternate strands 50 are connected to support rods 51 while the remaining filament strands have their free ends connected to support rods 52. Support rods 51, 52 are arranged alternately about the array. Support rods 51 are joined to and supported by support member or disc 53. The support rods 52 extend through apertures formed in support member 53 and are conductively joined to support member 54. Support members 53, 54 are insulatingly connected together as by bolt 55 and insulators 56, 57. As shown the support member 53 is connected adjacent its periphery to the inwardly presented peripheral portion of a tubular conductive member 58; insulation being provided between members 53 and 58 by means of insulators 59.

As was previously pointed out the lower ends of filament strands 50 are joined together. This is accomplished by welding each of the strands to a molybdenum or tungsten ring 60 as indicated generally at 61 in Figure 5. At the same time, a plurality of flexible radio frequency connectors in the form of thin, flexible strips of tantalum are connected as by welding to ring 60 between each of the filament strands. Flexible connectors in the form of bellows 62 are shown in Figure 5 while flexible connectors in the form of substantially flat strips 63 are shown in Figure 4. One end portion of flexible connectors 62 or 63 is connected to ring 60 while the other end of each connector is bolted or welded to conductive member 58.

Tubular conductive member 53 which serves to support members 53 and 54 as well as support rods 51, 52

and the filament strands 50, is sealed through the envelope wall and in the present instance forms part of the envelope wall. Annular insulating member 64 is sealed at one end, thereof, to conductive member 58 while the other end thereof is sealed to a terminal member 65, a portion of which is shown, which may be somewhat similar to terminal member 37 (Figure 1). Conductive member 58 is closed by a somewhat dish-shaped metallic header member 66 which is sealed along its peripheral portion to the peripheral portion of member 58. Header member 66 has apertures formed therethrough which in the present instance are each closed by one of a pair of filament heater leads 67, 68, the outwardly projecting portions 67a, 68a of which serve as heater terminal members. A flexible conductor 69 such as a copper strap is connected to one end of lead-in 67 and its other end is connected to support member 54. The other filament heater lead-in 68 is similarly connected to support member 53 by means of flexible conductor 70.

It is to be noted that the radio frequency connectors join the inwardly presented end of tubular member 58 to the electrical center of the filament array. Since adjacent filament strands 50 form a connection between the adjacent pairs of support rods 51, 52, the filament heating current which enters the device, say along lead-in 67, flows along support member 54 to each of the support rods 52. Then the filament heater current flows down each of the filament strands 50; the ends of which being connected to support rods 51. Finally the heater current circuit is completed through support rods 51, support member 53, conductor 70 and lead-in 68.

The outwardly extending portion 58a of member 58 functions as the filament radio frequency terminal member. Connection to terminal member 58 may be readily made, as described in connection with tube 10, by means of a hollow tubular member which may form part of a coaxial transmission line. Here again, the filament heater current is separated from as well as shielded from the radio frequency elements and circuit. It is believed clear that the radio frequency current path within such a device is essentially a continuation of the circuit outside the same as brought out in connection with tube 10. Such arrangements which are illustrated by conductive members 29 and 58 provide low impedance uniform radio frequency paths which are continuous right up to each of the filament strands themselves. In accordance with my invention a uniform equi-potential filament structure is provided which may be operated at high temperature and has substantially all of the advantages heretofore afforded by solid indirectly heated cathodes from a circuit standpoint without the limitations heretofore imposed by such structures.

While I have described my invention in detail in connection with the specific forms thereof shown by way of exemplification it is believed obvious that changes and variations may be made therein without departing from the scope of my present invention. Furthermore, while my invention may be particularly useful in high frequency and high power electron tubes it also may be used to advantage in other types of tubes. For example, the equal distribution of radio frequency current among the various filament strands which is effected in accordance with my invention, results in uniform heating of the strands due to the flow of the radio frequency current therein. Thus harmful deformation or warping of the structure which has heretofore resulted from uneven radio frequency heating is avoided. It is therefore intended to cover all modifications and variations of my invention which come within the scope of the appended claims.

What is claimed is:

1. An electron tube comprising an envelope, a plurality of electrodes spaced in said envelope and including a fila-

mentary cathode and another electrode, a plurality of elongated conductive support members in an annular array, said filamentary cathode comprising a plurality of filament strands in an annular array, said array of filament strands being interposed between said other electrode and said array of support members, heating current lead-in and support means connected to said support members adjacent one end thereof for applying heating current to said filament strands, each of said filament strands being connected adjacent one end thereof to the other end portion of one of said support members, a lead-in and support for said other electrode, and a lead-in for radio frequency current interposed in said envelope between said heating current lead-ins and the lead-in for said other electrode and connected to the other end portions of each of said filament strands.

2. An electron tube comprising an envelope, a plurality of electrodes spaced in said envelope and including a plurality of cathode filament strands in an annular array with the remaining electrodes all on one side of said array, an annular cathode terminal member interposed in said envelope, a tubular conductive member connected to said cathode terminal member and to each of said filament strands adjacent one end thereof, heating current lead-ins on one side of said cathode terminal member providing the sole heater current path, a plurality of conductive support members connected adjacent one end thereof to said heating current lead-ins and forming an annular array on the side of said cathode filament array away from said remaining electrodes, said support members extending into said envelope beyond said tubular conductive member, and each of said filament strands being connected adjacent the other end thereof to the inner end portion of one of said support members.

3. An electron tube comprising an envelope, a plurality of coaxial, concentric electrodes spaced in said envelope and including a plurality of cathode filament strands in an annular array, an annular cathode terminal member for radio frequency current interposed in said envelope, a tubular conductor for radio frequency current connected to said cathode terminal member extending adjacent to one end of said filament strand array and connected thereto, heating current lead-ins for supplying heating current to said filament strands and extending into said envelope interiorly of said cathode terminal, a plurality of filament support members in an annular array coaxial and concentric with said filament strand array and within the same, said support members extending through said tubular conductor with the inner ends thereof spaced axially inward of said tubular conductor, and the end portion of each of said filament strands remote from said tubular conductor being connected to the inner end portion of one of said support members.

4. An electron tube as defined in claim 3 wherein said filament strands are substantially hairpin-shaped, and said tubular conductor is connected to substantially the electrical center of each of said strands.

5. An electron tube comprising an envelope, a plurality of cathode filament strands in an annular array, coaxial concentric control and anode electrodes spaced about said cathode array, annular cathode, control and anode terminal members interposed in said envelope in that sequence and insulated one from the other, the diameter of said cathode terminal member being the smallest, the diameter of said anode terminal member being the largest, the diameter of said control electrode terminal member being intermediate that of said cathode and anode terminal members, concentric coaxial tubular conductive members connecting said cathode and control electrode terminal members respectively to one end of said filament strand array and to said control electrode, and heating current supply and support means forming with said filament strands the sole path for heating current, said means including a pair of heating current lead-ins extend-

ing through said envelope interiorly of said cathode terminal member, a plurality of conductive support members in an annular array and connected adjacent one end thereof to said lead-ins, said support members extending through the tubular conductive member connected to said filament strand array, the end portion of each of said filament strands remote from the tubular conductor connected thereto being connected to the inner end portion of one of said support members.

10. An electron tube comprising an envelope, a plurality of electrodes spaced in said envelope and including a filamentary cathode and another electrode, a plurality of elongated conductive support members in an annular array, said filamentary cathode comprising a plurality of filament strands in an annular array, said array of filament strands being interposed between the other electrode and said array of support members, a pair of coaxial concentric tubular heating current lead-ins sealed through said envelope, support means connected to said heating current lead-ins and to said support members adjacent one end thereof, each of said filament strands being connected adjacent one end thereof to the other end portion of one of said support members, a lead-in and support for said other electrode, and a lead-in for radio frequency current interposed in said envelope between said heating current lead-ins and the lead-in for said other electrode and connected to the end portions of each of said filament strands remote from said support members.

7. An electron tube comprising an envelope, an annular array of a plurality of cathode filament strands, an annular array of a plurality of conductive support members spaced radially inward of said filament strands with said filament strands extending downward along the same, the inner end portions of each of said filament strands being connected to the inner end portion of one of said support members, a pair of nested conductive tubular lead-ins sealed through said envelope in insulated relation, alternate ones of said support members being connected to one of said lead-ins, the remaining support members being connected to the other of said lead-ins, an annular cathode terminal member interposed in said envelope and insulatedly sealed to the outer one of said lead-ins, said cathode terminal member engirdling said lead-ins and being adjacent to the inner ends thereof, and a tubular conductive member joined adjacent one end to said cathode terminal member and adjacent the other end to the end portions of said filament strands remote from said support members.

8. An electron tube comprising an envelope containing a cathode, said cathode including a pair of cathode filaments, a tubular cathode terminal and support member connected to said filaments at one end thereof, and a pair of filament terminal members extending in insulating relation through the tubular opening of said cathode terminal and support member and connected respectively to said cathode filaments at the other end thereof.

9. An electron tube comprising an envelope containing a cathode, said cathode including a pair of cathode filaments, a grid adjacent to said cathode, a tubular cathode terminal and support member forming part of said envelope connected to all of said filaments at one end thereof, a tubular grid terminal and support member surrounding said cathode terminal and support member, and a pair of filament terminal members extending in insulating relation through the tubular opening of said cathode terminal and support member and connected respectively to said cathode filaments at the other end thereof.

10. An electron tube comprising an envelope containing a cathode, a grid adjacent to said cathode, a tubular radio frequency cathode terminal connected to said cathode and forming a part of said envelope, a tubular radio frequency grid terminal of larger diameter than said cathode terminal connected to said grid and forming a part of said envelope, and means for conducting heating current to said cathode including terminal means surrounded by said cathode terminal, said cathode terminal forming

the inner-most extension of a re-entrant portion of said envelope.

11. An electron tube comprising an envelope, a plurality of cathode filament strands, grid and anode electrodes spaced from said cathode filament strands, a pair of heating current lead-ins extending into said envelope at one end thereof and connected to said filament strands, an annular cathode terminal member surrounding said pair of heating current lead-ins, an annular grid electrode terminal member surrounding said pair of heating current lead-ins and having a diameter larger than said cathode terminal member, said pair of heating current lead-ins, said cathode terminal member and said grid electrode terminal member being insulatingly sealed to each other and to said anode electrode, said cathode terminal member forming the inner-most extension of a re-entrant portion of said envelope.

12. An electron tube as defined in claim 5 wherein said heating current lead-ins, said cathode terminal member, said control electrode terminal member, and said anode terminal member comprise a re-entrant portion of said envelope.

13. An electron tube comprising a filamentary cathode, co-axial and concentric control, screen, and anode electrodes, support and heating current lead-in means comprising a first tubular conductor having a terminal portion at one end thereof, and a second tubular member co-axial with and having a larger diameter than said first tubular

member surrounding the other end portion of said first tubular member, an annular cathode terminal member surrounding said other end of said first tubular member and said second tubular member and insulatingly sealed to said second tubular member, an annular control electrode terminal member insulatingly sealed to said cathode terminal member and extending toward said terminal end of said first tubular member, an annular screen electrode terminal member insulatingly sealed to said control electrode terminal member extending toward and surrounding said terminal end of said first tubular member; whereby said first tubular member, said second tubular member, said control electrode terminal member, and said screen electrode terminal member form a double re-entrant portion of the envelope of said electron tube.
